UNITED STATES PATENT OFFICE.

CHARLES H. J. DILG, OF NEW YORK, N. Y.

ADJUSTABLE SELF-CLAMPING BRACKET.

SPECIFICATION forming part of Letters Patent No. 766,605, dated August 2, 1904.

Application filed July 1, 1903. Serial No. 163,909. (No model.)

To all whom it may concern:

Be it known that I, CHARLES H. J. DILG, a citizen of the United States of America, and a resident of New York, in the county and State 5 of New York, have invented a certain new and useful Adjustable Self-Clamping Bracket, of which the following is a specification.

My invention relates to supporting-plates or combination of plates ordinarily of moderate projection generally springing from a vertical surface and in particular to an adjustable metal plate of suitable configuration that may be engaged with and locked to and also detached at will from any support desired in order to serve as a means of holding articles; and it has for its object the provision of a device of the kind set forth simple in construction, inexpensive to manufacture, and efficient in practical use.

20 To attain the desired end, this my invention consists in novel devices and combinations of devices hereinafter described.

In order to enable my invention to be fully understood, I will proceed to explain the same 25 by reference to the drawings, which accompany and form a part of this specification, in which—

Figure 1 represents a side elevation of one 30 of my brackets and support therefor. Fig. 1^a is a plan view, and Fig. 1^b a rear elevation, of the same. Fig. 1^c is a view in detail of my locking joint. Fig. 2 is a side elevation of another bracket and support constructed according to my invention. Fig. 2^a is a plan 35 view, and Fig. 2^b a rear elevation, of the same. Fig. 3 is a side elevation of another one of my brackets and support. Fig. 3^a is a plan view of the same, and Fig. 3^b a view in detail of the end of the bracket and holding-plates 40 thereof. Fig. 4 is a side elevation of another bracket and support constructed according to my invention. Fig. 4^a is a plan view of the same, and Figs. 4^b and 4^c are respectively views in detail of my locking and clamp- 45 ing devices. Fig. 5 is a side elevation of another one of my brackets and support. Fig. 5^a is a plan view of the same. Fig. 6 is a side elevation of another bracket and support constructed according to my invention. Fig. 6^a is a plan view of the same; and Fig. 6^b a view 50

in detail, partly in section, of my clamping means. Fig. 7 is a side elevation, and Fig. 7^a a plan view, of another one of my brackets and support.

Like letters of reference indicate like parts 55 in all the views.

I have found it desirable to produce a self-clamping bracket that may be engaged with a support and adjusted to any desired height or inclination and locked in said position and 60 that may be also detached from the said support at will without disturbing any other brackets attached to the said support that may be located above or below the said bracket, and I have therefore constructed according to 65 my invention a device of the class described embodying the preferred construction of parts and their mutual relationship, combination, arrangement, and organization in a composite body or structure, as hereinafter described. 70

Referring particularly to the drawings, A denotes a support consisting, in the present instance, of a metal rod.

B and B' are my holding-plates, consisting 75 of vertical parts curved at their rear portions in order to conform to the contour of the rod A and are preferably locked together by means of the engagement of the tongue b of the plate B with the slot b' of the plate B'. The plates B and B' are provided with similar vertical slots b² to form a seat for the pin C, the upper portion of each of which slots is extended forwardly in a horizontal direction 80 for a short distance in order to form a pocket or seat for the pin C when the same is moved 85 out of the slots b². The curved outer or front edges of the plates B and B' are preferably provided with a series of notches or recesses b³.

My bracket D preferably consists of a metal plate of suitable form or configuration, the 90 rear portion of which is provided with a series of bearing-surfaces d, preferably eccentrically disposed as regards the seat of the pin C in the slots b² and intermediate recessed portions d' and also carries a pin C. The 95 upper edge or face of my bracket is beveled, as at d², and my bracket is also provided with a slot E, in the end of which is fastened a pin F, carrying a movable locking-plate f, and a spring f', located rearward of the same. 100

After the plates B and B' are clasped to the rod A and moved up or down, if necessary, until in the required adjusted position as regards height the rear end of the vertically-held bracket D is inserted between the two plates, the beveled edge portion d^2 being adjacent to the said rod until the pin C reaches the top of the slots b^2 . Then by turning the bracket outwardly from its approximately vertical position until the desired inclination is secured, and thus operating my preferably eccentrically engaging clamping means, one of the bearing-surfaces d will rest against the rod A and the pin C will be forced to travel into the horizontal extension of the slots b^2 . In order to rigidly lock the parts in the adjusted position after being thus clamped together, the locking head or plate f, which is normally held in the enlargement e of the slot 20 E, may be released from the same, and being carried forward by the resilience of the spring f' engages and is held in one of the recesses or notches b³.

It will thus be seen that my adjustable self-clamping bracket may be attached to and detached from the support A without the use of any extraneous parts, inasmuch as the adjustable support-engaging means, the eccentrically-working clamping means, and the locking means all form portions of my bracket, consisting in the device under consideration of three members—namely, the holding-plates B and B' and the bracket-plate D. In cases where there are a number of brackets held by a support additional brackets constructed according to my invention may be added to the support or their number reduced and their height and inclination varied without disturbing any of the others.

The rod A¹⁰ of the bracket shown in Fig. 2 is clasped by the holding-plates B¹⁰ and B¹¹, preferably provided with a dovetailed joint b¹⁰ and with slots b¹². The bracket D¹⁰ has a practically curved face consisting ordinarily of a series of eccentrically-located bearing-points d^{10} and a beveled portion, as d^{11} , and also carries a pin C¹⁰. My locking means consists of a series of orifices d^{10} , formed in the bracket, and an orifice b¹¹, located in the plate B¹⁰ and constructed and arranged to register with the former at different inclinations of the bracket. A pin G, carried by a plate g, which works on a post g', supported by the plate B¹⁰, is constructed and arranged to enter one of the orifices d^{12} and the orifice b¹¹ when they register with each other and is held in a locking position by the spring g². When the parts are not in a locked relation, the edge of the pin G may be raised a sufficient distance to rest on the plate B¹⁰.

In the bracket constructed according to my invention and shown in Fig. 3 the holding-plates B²⁰ and B²¹ are inserted in the channel-support A²⁰, and when the bracket D²⁰, which is U-shaped in cross-section, is placed in the

said support the preferably eccentric bearing-surfaces d^{20} work against the rear face of the channel-support and the outwardly-turned edges b²⁰ and b²¹ of the plates B²⁰ and B²¹ bear against the inwardly-turned edges a²⁰ of the 70 said support.

The holding-plates B³⁰ and B³¹ and the bracket D³⁰ (shown in Fig. 4) are loosely held to the support A³⁰ by means of the screw H and wing-nut H', and after the bracket is positioned by operating the eccentrically-located engaging clamping means the parts are rigidly locked in position by the engagement with the milled bearing h' of the screw H of the serrated orifices b³⁰ and d³⁰ of the bracket D³⁰ 80 and holding-plates B³⁰ and B³¹.

In the bracket shown in Fig. 5 the channel-support A⁴⁰ is provided, preferably, with a series of movable parts T-shaped in cross-section and consisting of a web a⁴⁰ to work in 85 the slot of the channel, connecting an elongated widened part a⁴¹ to bear against the inner channel-faces adjacent to the slot, and an approximately circular portion a⁴², provided on its periphery with recesses a⁴³ and at its center with a pin a⁴⁴. The U-shaped bracket D⁴⁰ is provided with a slot d⁴⁰, the lower part of which is turned rearwardly, and also with a dog d⁴¹, carrying a locking-pin d⁴² and a spring d⁴³. The bracket D⁴⁰ upon being engaged with the support is held in a vertical position or parallel to the support A⁴⁰, the smaller end of the same extending upwardly. The locking-pin d⁴² is held away from the end of the slot d⁴⁰ and the part d⁴² is entered between the two sides of my bracket, the pin a⁴⁴ entering the longer portion of the slot d⁴⁰, which now lies in a horizontal position. By now pushing the bracket toward the support and turning the same a little the pin a⁴⁴ will 100 enter the shorter part of the slot and rest against the end of the same, which forms a seat or bearing for the pin a⁴⁴. Then by turning the bracket in a downward direction the preferably eccentrically-located engaging bearing-surface d⁴⁵ of the bracket will engage 105 with the outer face of the channel-support, whereby the bracket may be clamped to the support in any one of a number of desired predetermined positions or at any predetermined 110 inclination with respect thereto, the bracket being thus held in a relatively changeable and detachable relation. After the bracket has been adjusted or moved to any desired height and predetermined inclination or position the 115 pin d⁴² may be entered in the slot d⁴⁰ and engaged with any one of the series of recesses a⁴³, thus locking the parts rigidly together. By manipulating the locking-pin d⁴² and moving the bracket upwardly again it may be 120 readily and quickly disengaged from the support.

The bracket shown in Fig. 6 is provided with a slot d⁵⁰, having rearwardly-extending recesses d⁵¹, and carries a bifurcated T-shaped 130

pivoted dog J and a loose eccentrically-disposed dog K, provided with a pin k working in the slot d^{50} , the two dogs being preferably connected by a spring L. The head or 5 free end of the dog J is rectangular in form and is so constructed and arranged that when held lengthwise with and parallel to the channel-support A⁵⁰, the bracket being in a vertical position, it may be slipped in the slot 10 thereof, after which the bracket may be turned around so as to assume a horizontal direction, whereupon the ends of the dog J will bear against the interior of the front wall of the channel-support A⁵⁰ and the neck of the same 15 will work in the channel-slot. The end of the preferably eccentrically-disposed dog K is formed with a central projection or nose k' to enter the slot of the channel and with preferably milled portions k² to bear against 20 the preferably milled outer face d⁵⁰ of the channel-support. After the bracket is positioned the parts may be locked by the engagement of the pin k with one of the recesses d⁵¹ and the end of the dog K with the 25 channel-support and the neck of the dog J. In Fig. 7 the bracket is similarly formed except that the end of the dog K⁶⁰ is curved or formed in hook shape in order to be slipped on and off the supporting-rod A⁶⁰, and the 30 face of the dog K⁶⁰ is made concave in cross-section in order to conform to the curved face of the support.

It is manifest that various omissions of some particulars could be made without materially 35 affecting the essential features of my invention or the operation of the remaining parts, and I do not, therefore, wish to be limited to the specific structural details of the organization herein set forth. Obviously the elements of the structure described may be located at an angle to the plane in which they 40 are shown. I accordingly use the words "horizontal," "vertical," and the like in a relative sense.

45 In operation a bracket constructed according to my invention may be applied to a support at any point of the said support in the manner described—that is to say, it may be inserted between two brackets already positioned in a show case or window and serving to display articles of wear or other goods without disturbing any of the said brackets or rearranging the said window display, or one of the group of brackets may be removed 50 without having to manipulate the other brackets. My bracket may be disengaged from the support by reversing the operation described of engaging and attaching the bracket to the said support.

Inasmuch as my bracket preferably engages 60 the support eccentrically in order to clamp the bracket thereto, it may be not only attached to and detached from the support without disturbing the other brackets by which it may be surrounded, but it may also be rigidly 65 locked to the support at any height or at any inclination desired in respect to the said support.

As it is evident that many changes in the construction, form, proportion, and relative 70 arrangement of parts might be resorted to without departing from the spirit and scope of my invention, I would have it understood that I do not restrict myself to the particular construction and arrangement of parts shown 75 and described; but that such changes and equivalents may be substituted therefor, and that—

What I claim as my invention is—

1. A support, in combination with an adjustable self-clamping bracket provided with means to lock the bracket to the support at different heights and inclinations.

2. In combination, a support and a bracket, and means constructed and arranged to engage 85 the support at any point of said support to clamp the bracket thereto and also to rigidly lock the parts together at a number of predetermined inclinations of the bracket with respect to the support, and also to detach the 90 bracket from the support at will.

3. A support, in combination with an adjustable self-clamping bracket provided with means to engage the support at any point of said support at a number of desired inclinations, and to detach the bracket therefrom at 95 will.

4. In combination, a support and a bracket, and means constructed and arranged to engage the support eccentrically to clamp the bracket 100 thereto and to rigidly lock the parts together at a number of desired inclinations.

5. In combination a support and a bracket, and means constructed and arranged to engage the support eccentrically at any point of said 105 support to clamp the bracket thereto, and to rigidly lock the parts together at a number of desired inclinations, and to detach the bracket from the support at will.

In testimony of the foregoing specification 110 I do hereby sign the same, in the city of New York, county and State of New York, this 20th day of May, A. D. 1903.

CHARLES H. J. DILG.
